UNITED STATES PATENT OFFICE.

THOMAS HARDING, OF NEWARK, NEW JERSEY, ASSIGNOR TO J. L. SOMMER MANUFACTURING CO., A CORPORATION OF NEW JERSEY.

MILK-BOTTLE HOLDER.

Application filed March 24, 1923. Serial No. 627,508.

This invention relates in general to article holders or supports of the type comprising a spring clip adapted to be fixedly secured to a vertical support, and more particularly to 5 a holder of this character for milk bottles.

The primary object of the invention is to provide a simple device of the character described formed of a single piece of heavy wire or metal rod which can be fastened to a support 10 with fastening members such as screws, nails, etc., so that the holder cannot work loose or its holding qualities become impaired by continued use.

Further objects are to provide such an 15 article holder comprising a single piece of resilient heavy wire or metal rod formed with a substantially circular or looped base having a middle portion flattened in the plane thereof with one face of the flattened portion 20 substantially flush or continuous with one face of said base to form a flat surface of extended area for engaging a support, said flattened portion being provided with a transverse opening at each side of the base to receive a fastening member; to provide arms 25 which have substantially parallel portions projecting outward from the extremities of free end portions of the base with oppositely bowed portions at the extremities of said substantially parallel portions to receive an article 30 between them; to thus secure very effective and lasting resiliency in said arms; to provide a holder of the character described which shall be inexpensive and yet strong and durable, and to obtain other results and advantages as may be brought out by the following 35 description.

Referring to the accompanying drawings, in which like numerals of reference indicate 40 the same parts throughout the several views,

Figure 1 is a front elevation of a milk bottle holder constructed in accordance with my invention;

Figure 2 is a side elevation thereof, and

Figure 3 is a top plan view.

The holder constructed in accordance with my invention comprises a single piece of resilient heavy wire or metal rod substantially circular in cross-section bent to form a substantially circular or loop-shaped base in substantially a single plane and arms bent at substantially right angles to the plane of said base and shaped as at 2 to conform to an article to be supported, in the present instance 55 a milk bottle. The middle part of said base is

flattened from one face thereof, as indicated at 3, in any suitable manner as by means of a press, said flattened portion being substantially parallel to the plane of the base and the face thereof opposite the extremities of the arms 60 2 being substantially flush and continuous with the surface of the unflattened portions 1 of the base, as indicated at 4. The face of the base A opposite the extremities of the arms is thus substantially flat for an extended 65 area, as indicated at 5, to solidly engage a support to which the holder is to be secured. The flattened portion 3 also admits of openings 6 being formed in the base opposite each other to receive screws 7 or similar fastening members 70 for securing the holder to a support. Also, the flattened portion 3 permits the stamping of advertising matter thereon.

The unflattened end portions 1 of the base are free and the arms have substantially parallel portions 8, 8 bent sharply outward from said free end portions, the oppositely curved bottle-engaging portions 3 of the arms being at the ends of said substantially parallel portions 8, 8. Thus, when the holding arms 80 are spread the free end portions 1 of the base also bend or raise slightly away from the surface to which the base is secured, thus securing an action which results in a very flexible resiliency and one which at the same 85 time is very durable. That is to say, the holding arms grip the article securely and firmly, and yet they do not become permanently bent apart by repeated use so as to impair their holding qualities. The device 90 is therefore very durable and at the same time it is very simply made. The flattened portion 3 of the base very effectively resists any tendency of the base to tilt upon the line of its fastening screws due to the insertion and removal of articles between the holding arms.

The construction of the holder also enables the arms to be spread apart or forced together before the holder is secured to a support in 100 order to adapt it to receive articles of different sizes, without in any way impairing the fixed and secure attachment of the holder to a support, and when the holder is secured to a support the screws 7 prevent undue spreading of the arms. The holder may be secured to a support in any desired position, but preferably is so arranged that the extremities 2 of the arms are lowermost so that there is less tendency of the weight of the 110

article to bend the arms relatively to the base A.

Having thus described the invention, what I claim is:

- 5 1. A milk bottle holder composed of a single piece of resilient wire with its middle portion forming a substantially circular attaching base and its end portions projecting from a marginal point of said base and forming oppositely bowed gripping arms lying in a plane at substantially a right angle to said base, said base being of a diameter 10 enough greater than the distance between the arms adjacent said base to stably support them and having substantially at opposite ends of a diameter parallel to the plane of the 15 gripping arms means for fastening said base flatwise against a wall so as to leave its portion between said fastening means and the gripping arms free, the portion of the base on the opposite side of said diameter being 20 flattened in the plane of the base.

arms and exerting both flexing and torsional resistance against spreading of the arms.

2. A milk bottle holder composed of a single piece of resilient wire with its middle portion forming a substantially circular attaching base and its end portions projecting from a marginal point of said base and forming oppositely bowed gripping arms lying in a plane at substantially a right angle to said base, said base being of a diameter 25 enough greater than the distance between the arms adjacent said base to stably support them and having substantially at opposite ends of a diameter parallel to the plane of the 30 gripping arms means for fastening said base flatwise against a wall so as to leave its portion between said fastening means and the gripping arms free, the portion of the base on the opposite side of said diameter being 35 flattened in the plane of the base.

THOMAS HARDING.
